UNITED STATES PATENT OFFICE.

JOSEPH H. WITTMANN, OF KANSAS CITY, MISSOURI.

TENT.

1,290,824.

specification of Letters Patent.

Patented Jan. 7, 1919.

Application filed May 5, 1916. Serial No. 95,584.

To all whom it may concern:

Be it known that I, JOSEPH H. WITTMANN, a citizen of the United States, residing at Kansas City, in the county of Jackson and State of Missouri, have invented certain new and useful Improvements in Tents; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to tents, and has for its principal object to provide a tent which is especially adapted for automobile touring, or other out-door uses, in that it may be easily and quickly erected to form a water and insect-proof sleeping compartment, and may be folded to form a compact bundle which may be easily handled and will occupy a minimum amount of space in transportation.

20 25 In accomplishing this object I have provided the details of structure hereinafter described and illustrated in the accompanying drawings, wherein:—

Figure I is a perspective view of a tent constructed according to my invention, illustrating the manner of suspending the tent from an automobile, and showing it in connection with a bed.

Fig. II is a perspective view of the tent, particularly illustrating the opening, a part of the tent being broken away to show the pockets.

Fig. III is a longitudinal vertical section of the same.

40 Fig. IV is a detail perspective view of a bracket for supporting the inner end of the bed on the foot-board of an automobile.

Fig. V is a detail perspective view, showing the manner of fastening the tent supporting straps to an automobile top.

Fig. VI is a sectional view of a modified form of flap and pocket, as used with a full length tent wall.

50 Fig. VII is a detail view of part of a tent wall showing a modified arrangement of the flap.

Referring more in detail to the drawings:

1 designates a tent embodying my invention, and which is adapted for support on, or suspension from, the side of an automobile 2, of any ordinary construction compris-

ing a top 3 and foot-board 4, although the use of the tent is not limited to such combination, nor to the combination with a bed of the structure hereinafter described, the specific description of bed structure and the combination of the tent with an automobile and bed being given merely to better describe the structure and use of the tent.

5—6 designate respectively the inner and outer end bars of a bed and 7 a canvas, or the like, which connects the said bars and forms the carrying body of the bed; the bed shown and described herein being of the type more fully disclosed in my copending application, filed March 27, 1916, and serially numbered 86,974.

Projecting from the inner cross bar 5 of the bed are hooks 8, having out-turned end portions 9, and supported by socket members 10 on the under face of the foot-board 4 are brackets 11, comprising standards 12 provided at their upper ends with eyes 13, for receiving the end members 9 of the bolts 8 and having base portions 14 which are slidably secured within the sockets 10 by set screws 15.

Fixed to the outer bed bar 6 are spreader arms 16, which are of little more than half the length of the bed, and fixed to the inner end bar are supporting arms 17 that are adapted for engagement by the free ends of the spreader arms to form a leverage support for the outer end of the bed.

Each of the supporting arms is provided with a plurality of sockets 18 on its under face which is adapted for receiving a latch 19 on a relative spreader arm to provide adjustment for the bed, and with a tightening rope 20 that secures the end of each of the supporting arms to the end cross bar to tighten the spreader arms against the supporting arms to make the connection secure.

The preferred form of tent comprises the sloping top member 25, having integral side 100 and end walls 26—27 and an inner end wall 28; the side and end walls being secured at their adjacent edges and draped about the carrying body of the bed to inclose the same. The lower edges of said side and end walls 105 are turned up and sewed to the body (as at 29) at intervals along the walls and at the corners of the tent to form permanent pockets 30, the upturned portions extending beyond the stitching 29 to form flaps 31 that 110 may lie on the bed beneath the bed clothing to anchor the tent to the bed and vice versa.

The upturned portions need not be stitched to the body of the wall throughout the entire depth of the pockets, as by limiting the stitching to the upper portions of the pockets a single continuous pocket may be formed entirely about the bed. The loose ends of the upturned edge portions of the tent walls and the flaps 31 are cut on a bevel at the corners and sewed together, as at 32, so that the tent body is made to snugly fit the bed.

Secured to the upper corners of the top 25 are supporting strips 33-33' which are adapted for overlying the automobile top 2, 15 and are provided at their free ends with button-holes 34 for receiving buttons 35 on the automobile top and at the side of the vehicle opposite that on which the tent is placed and by which means the tent is held erected.

20 At either side or at the end of the tent I provide an opening by separating the side and end members, and provide the same with buttons 37 by which the flaps 38 may be held closed. A supplemental flap 39 is 25 also sewed to the end member 28 and may be buttoned over the side flap after the same has been fastened to close the opening, so that rain cannot be blown into the tent.

I also provide ventilating openings 40 in 30 each of the side walls and close the same with a screen 41 to prevent mosquitos, or bugs, from entering, and I provide flaps 42 for the openings which may be raised or lowered from the inside of the tent by 35 means of drawstrings 43-44 which are secured to the free ends of the flaps and pass through apertures 45 in the side walls, so that one may manipulate the strings from the inside of the tent to raise or lower the 40 flaps.

To hold the tent securely over the bed, I provide buttons 47 at the ends of the end bars 5-6, which may be projected through button holes 48 at the corners of the tent, 45 and provide a cross strip 49 which is secured to the opposite side members and overlies the bed, so that when the bedding is laid thereon the side walls are held in position. If so desired, tapes 50 may be attached to the tent sides and ends and tied to the bed bars to hold the walls of the tent down and anchor the tent to the bed.

With some forms of supports, as when the bed and tent are carried by the trailer 55 of an automobile, it is desirable for the tent walls to extend to the ground instead of folding up at their lower edges to form the pockets. In such cases the walls may hang along the sides of the bed to the ground and separate pieces 51 attached to the inner faces of the walls by sewing or otherwise, and turned up to form the pocket and flap.

The strips 33-33' are then thrown over 60 the top of the automobile and secured to

the buttons 35 so that the tent is drawn tight above the bed. Bedding is then placed on the supporting body to overlie the cross strips 49 and pocket flaps 31 so that an inclosed compartment is formed 70 that is impervious to inclement weather or insects.

It will be seen that when a person retires within the tent, the clothing when removed, may be placed within the side or 75 end pockets, where it is protected from the weather and insects and will serve to hold the tent down about the bed.

In the modified form, I have shown a tent flap extended to the ground and having a separate pocket portion sewed to the side wall; this construction being used on large tents where the side walls are extended to the ground.

It is apparent that by so constructing 85 the tent and bed a very convenient and serviceable combination is provided that may be easily and quickly erected and when not in use may be folded together to form a compact bundle that is easily transported 90 and requires a minimum amount of space.

While I have shown a particular kind of bed, it is apparent that any type of cot or bed could be used, and it is also apparent that the tent could be supported in any 95 suitable manner without departing from the spirit of the invention.

It is also apparent that with a tent of this construction it is unnecessary to provide guy ropes, as the tent walls are anchored 100 by the bed.

While the pocket that is formed by the anchoring flap is a great convenience for holding clothing, or the like, the flap may overlie the bed without forming the pocket, 105 and when so arranged will be fully as effective for excluding insects from the interior of the tent.

Having thus described my invention, what I claim as new therein, and desire to 110 secure by Letters-Patent, is:

1. In combination with a bed, a tent enclosing the bed, having a side wall extending below the bed bottom and comprising a member having a free edge turned inwardly along the bed bottom above the 115 bottom of the side wall.

2. The combination with a bed, of a tent comprising a wall and a pocket member connected with the wall and having a flap 120 at its free edge supported on said bed.

3. The combination with a bed, of a tent having walls draped about and extending below the bed, the edges of said wall being turned up to overlie the edges of the bed, 125 for the purposes set forth.

4. The combination with a bed, of a tent having side and end walls draped about and extending below the bed and turned up 130 to overlie the edges thereof to form pocket-

ets thereabout between the said outer and upturned portions, and a strip fastened to opposite points on the side walls adapted to closely overlie the bed.

5. 5. The combination with a bed, of a tent having side and end walls draped about the bed and extending below and turned up to overlie the edges thereof to form pockets thereabout between the said outer and upturned portions, and strips secured to the top of the tent for supporting the same above the bed.

6. The combination with a bed, of a tent comprising side and end walls and a slop-

ing top portion, there being an opening 15 between a side and end wall, and there being ventilating openings in the side walls; the said walls being draped about and extending below the edges of the bed and having their lower ends turned up to overlie the edges of the bed and form pockets there about, a strip for connecting opposite side walls, and strips secured to the top of the tent to suspend the same above the bed.

In testimony whereof I affix my signature.

JOSEPH H. WITTMANN.
